UNITED STATES PATENT OFFICE.

ARMAND H. PEYCKE, OF CHICAGO, ILLINOIS, ASSIGNOR TO AMERICAN STEEL
FOUNDRIES, OF CHICAGO, ILLINOIS, A CORPORATION OF NEW JERSEY.

MEANS FOR SUPPORTING BRAKES.

1,315,397.

Specification of Letters Patent.

Patented Sept. 9, 1919.

Application filed February 13, 1918. Serial No. 217,005.

To all whom it may concern:

Be it known that I, ARMAND H. PEYCKE, a citizen of the United States, and resident of Chicago, in the county of Cook and State 5 of Illinois, have invented certain new and useful Improvements in Means for Supporting Brakes, of which the following is a specification.

This invention relates to means for supporting brakes.

It has for its object to support brake mechanism, and especially brake beams in a manner to facilitate the braking and releasing action of the brake beam, and at the 15 same time leveling the beam in an improved manner.

This and other objects are accomplished by providing, in combination, a brake beam, a bracket, and a pivotal connection between 20 said bracket and the brake beam whereby the latter is free to oscillate.

The invention is illustrated on the accompanying sheet of drawings, in which—

Figure 1 is a side elevation, parts being in 25 section, of a railway car truck embodying my invention;

Fig. 2 is a fragmentary side elevation of the same on an enlarged scale, parts being in section; and

Fig. 3 is a detail plan view of the suspension arrangement shown in Figs. 1 and 2.

The various novel features of my invention will be apparent from the following description and drawings and will be particularly pointed out in the appended claims.

By referring to the figures of the drawing, it will be noted that I have shown a car truck, including a spring plank 10, to which are secured hangers 11 for supporting a 40 horizontally extending rigid safety bar 12, the ends of which underlie brake beams 13 for the purpose of preventing the brake beams from falling to the tracks in the event that the beams are accidentally disconnected 45 from their normal hangings.

Brake beams of the truss type, herein shown as having a compression member 14 and tension member 15, have a tendency to tilt forwardly as normally hung by hangers 50 which are connected to the brake heads which are secured to the ends of the brake beam. To overcome this tilting effect of the tension member of the beam, leveling or supporting means must be provided. In this

particular case I have provided a pedestal 55 or bracket 16, which preferably is adjustably mounted upon the safety bar 12, and preferably near the ends thereof. The bracket preferably is rigid and extends upwardly and laterally inward toward the 60 center of the car. Pivots connected to the upper ends of the bracket 16 by a pin 17 is a link 18, the free end of which is provided with a loop portion 19 for the reception of the tension rod 15 of the brake beam. The 65 upper end of the bracket 16 preferably is bifurcated to receive the link 18 between its jaws, the jaws extending parallel with the line of movement of the brake beam during its application and releasing movements. It 70 will be understood that this supporting arrangement is at both ends of the safety bars and at each side of the truck.

By means of this arrangement the brake beams are permitted free forward and backward movement during the application and release of the brakes. At the same time the beams are provided with the underlying safety bars to prevent an accident which might occur by the brake beams falling to 80 the tracks. At the same time the arrangement is compact and simple and adapted to meet the various requirements for successful commercial operation.

It is my intention to claim all modifications of the invention falling within the spirit and scope of the following claims.

I claim:

1. In combination, a brake beam, a rigid safety bar therefor, a bracket adjustably connected to said safety bar, and a pivotal connection between said bracket and beam whereby the latter is supported.

2. In combination, a brake beam, a rigid safety bar therefor, a bracket connected to 95 said safety bar, and a link pivotally connected to the bracket and to the beam whereby the latter is supported for a swinging movement.

3. In combination, a brake beam, a safety 100 bar underlying the same, a bracket supported by the safety bar and extending laterally inwardly therefrom, and a link connecting the bracket and the brake beam whereby the latter is supported for a swinging 105 movement.

4. In combination, a truss brake beam, a rigid safety bar underlying the same, a

bracket connected to said safety bar, and a link connecting said bracket with the tension member of said brake beam for supporting and leveling the brake beam.

5. In combination, a brake beam, a safety bar underlying the same, a bracket connected to said safety bar and extending upwardly and laterally with respect to the safety bar, and a link connecting the bracket

and the beam for supporting the latter for 10 a swinging movement.

Signed at Chicago, Illinois, this 26th day of January, A. D. 1918.

ARMAND H. PEYCKE.
